US0D1112046S

(12) **United States Design Patent** (10) **Patent No.:** **US D1,112,046 S**
(45) **Date of Patent:** **** Feb. 10, 2026**

(54) **BATTERY**

(71) Applicant: **GS Yuasa International Ltd.**, Kyoto (JP)
(72) Inventors: **Kazuya Okabe**, Kyoto (JP); **Yoshihito Takagi**, Kyoto (JP); **Ryoichi Okuyama**, Kyoto (JP)

(73) Assignee: **GS Yuasa International Ltd.**, Kyoto (JP)

(**) Term: **15 Years**

(21) Appl. No.: **35/520,499**

(22) Filed: **Apr. 5, 2023**

(80) **Hague Agreement Data**

Int. Filing Date: **Apr. 5, 2023**

Int. Reg. No.: **DM/228409**

Int. Reg. Date: **Apr. 5, 2023**

Int. Reg. Pub. Date: **Apr. 5, 2024**

(30) **Foreign Application Priority Data**

(57) **CLAIM**

The ornamental design for a battery, as shown and described.

DESCRIPTION

1.1 is a front elevation view of the battery, showing the design, the rear elevation view being a mirror image;

1.2 is a top plan view thereof;

1.3 is a bottom plan view thereof;

1.4 is a right side elevation view thereof;

1.5 is a left side elevation view thereof;

1.6 is an enlarged front elevation view thereof of portion A-A in 1.1, the rear elevation view being a mirror image of the front elevation view;

1.7 is an enlarged right side elevation view thereof;

1.8 is an enlarged perspective view thereof of portion A-A in 1.1; and

1.9 is a perspective view thereof.

The dash-dash broken lines in the reproductions illustrate portions of the article that form no part of the claimed design. The dot-dash broken lines illustrate the boundaries of the claim and form no part of the claimed design.

1 Claim, 9 Drawing Sheets
